BALL MILL PULVERIZER

Martin Frisch, New York, N. Y., assignor to
 Foster Wheeler Corporation, New York, N. Y.,
 a corporation of New York

Application October 20, 1931, Serial No. 569,919

8 Claims. (Cl. 83—9)

My invention relates to pulverizing apparatus and more particularly to pulverizing apparatus employing a plurality of metal grinding balls loosely arranged in the grinding chamber; that is, balls which have considerable latitude of free movement relative to each other, as distinguished from balls which operate in a groove, race or other defined path of movement.

5

In particular, my invention relates to pulverizers of the vertical axis type as distinguished from horizontal axis pulverizers.

The primary object of the present invention is to provide a pulverizer of the type set forth in which the balls not only contact the stationary and rotatable parts of the structure enclosing the balls, but also roll against each other, thus producing grinding by both crushing and attrition. Another object of the invention is to reduce liner wear by providing slow movement between the liner elements and balls immediately adjacent the liner relative to the movement of the more active balls. A still further object of the invention is to provide an efficient distribution of air in a pulverizer of the type referred to.

Other objects and the advantages of my invention will be made clear upon consideration of the following description of a preferred embodiment thereof taken in conjunction with the accompanying drawings, which form a part of this specification and of which:

Fig. 1 is a vertical cross-sectional view of a pulverizer embodying the invention and is taken on the line 1—1 of Fig. 2;

Fig. 2 is a horizontal cross-sectional view taken on the line 2—2 of Fig. 1;

Fig. 3 is a horizontal cross-sectional view taken on the line 3—3 of Fig. 1;

Fig. 4 is a horizontal cross-sectional view, looking upward, taken on the line 4—4 of Fig. 1;

Fig. 5 is a plan view of an element of the pulverizer shown in Fig. 1;

Fig. 6 is a cross-sectional view taken on the line 6—6 of Fig. 5; and

Fig. 7 is a bottom view of the member shown in Fig. 5.

The pulverizer is mounted on a suitable foundation 10. Immediately resting on the foundation is a base plate 11. Mounted on the base plate is a cylindrical casing or housing member 12 which, together with the base plate 11 encloses the grinding chamber 13, the lower portion of which constitutes a grinding zone. Heavy plates or liner members 14 line the lower inside portion of the chamber 13 and serve to provide a crushing and wearing face or surface. These liners are made

in a number of separate pieces so that they may be removed and replaced when worn. As shown in the drawings, the liners cover the base plate 11 within chamber 13 and line the sides upwardly to a point above the part of the chamber containing the balls. The liner portion may be considered as a stationary bowl constituting a grinding or crushing zone.

A plurality of balls 15 are loosely contained within chamber 13. A charging door 16 is provided for admitting the balls to the chamber. The balls are of different sizes, as shown. Initially, balls of different sizes are charged into the apparatus. After the apparatus has operated for some time and before the balls are all worn down, replacement balls may all be of large size since the balls wear down and become smaller depending on the length of time of use. Thus a periodic replacement of large size balls will result in the maintenance in the grinding zone of a plurality of different sized balls.

A shaft 17 is mounted centrally of the apparatus to rotate about a vertical axis and extends through the chamber 13. Depending from the base plate 11 is a housing or support 18 enclosing or carrying a roller bearing 19 and an adjustable step bearing 20. The shaft is supported on the step bearing and is journaled in the roller bearing. Mounted on shaft 17 between roller bearing 19 and step bearing 20 is a bevel gear 21. This gear 21 meshes with a bevel gear 22 mounted on a horizontal shaft 23, which may be driven from any suitable source. A stuffing box 9 is provided where the shaft 17 passes through base plate 11.

The housing 12 has a cover 24 on which is mounted a hollow supply member 25. A roller guide bearing 26 is mounted in member 25 and serves to journal the upper end of shaft 17.

Mounted on shaft 17 is a tubular feeding member 28 suitably secured thereto by webs 29. The tubular member is concentrically mounted with respect to the shaft 17 and constitutes a substantially large air inlet duct. It rotates with the shaft 17. Attached to the lower end of tubular member 28 is an impeller 30. Impeller 30 is formed with a plurality of outwardly extending arms or blades 31. These arms or blades 31 extend into the grinding zone and contact the balls 15. The arms or blades 31 are hollow and are open at the bottom, but closed at the top, permitting air and coal or other material to be ground to flow downwardly therethrough and out at the bottom thereof. Each arm or blade 31 is covered by a suitable liner element which may

be removably bolted or riveted thereto. Mounted on shaft 17 within the impeller 30 is a hub 33 from which webs 34 extend to the outer portion of the impeller.

5 Also mounted on shaft 17 at the lower part of the chamber 13 is what may be termed a slinger or expeller 35, shown in detail in Figs. 5, 6, and 7. The slinger is rotatable with the shaft 17. On its upper side it has outwardly extending ribs or 10 vanes 36. On its lower side it has curved air vanes 37 for drawing air upwardly through stuffing box 9 and preventing coal from entering the stuffing box.

Member 25 is connected to a source of air supply, as a fan 39, and connected to a source of fuel, as feeder 40. The cover 24 is provided with a tangential outlet 41 for the final product which may be a mixture of pulverized coal and air to be burned.

20 Separator or classifier plates 42 and 43 are provided within the apparatus, plate 42 being secured to member 28, and plate 43 being secured to the casing. A plurality of spaced projections 44 of curved configuration preferably may be provided 25 on either of these members in juxtaposition to the passage between them. They are preferably provided on the plate 42 so as to serve to throw entrained coal particles away from the path of flow between these plates. Obviously the projections 44 may be straight instead of curved 30 configuration.

The operation of the apparatus is as follows:

Air and the coal (or other material to be pulverized) are admitted through the member 25 35 from the fan 39 and the feeder 40, respectively. The air and coal pass downwardly through the tubular member 28. The coal in part passes directly into contact with the balls 15 and is ground thereby and in part falls onto the slinger 35 and 40 is thrown outwardly into the grinding zone. The air passes downwardly and through the insides of the impeller arms or blades 31 and internally into the mass of coal or other material being ground.

45 Shaft 23 is rotated and in turn rotates shaft 17, which in turn rotates the tubular member 28 and the impeller 30. The impeller contacts and moves the balls around in the chamber 13, the number of balls being sufficient for this action. 50 The space between the lower end of impeller 30 and the liner on the base plate 11 or bottom of the casing is of greater height than the diameter of the largest ball and the maximum external diameter of the impeller is less than the inside diameter of chamber 13 by an amount more than 55 equal to twice the diameter of the largest ball so that the clearance between the lowermost and outermost portions of the impeller and the bottom and side walls respectively of the casing is but 60 slightly greater than the diameter of the largest balls used in the casing. The balls, in normal operation, dispose themselves, as shown in Fig. 1, outside the impeller 30 and below the same over the entire bottom of the grinding zone outwardly 65 of the slinger 35. The coal is ground by the balls both by attrition and crushing.

The balls 15 are made of metal and are heavy. The larger balls will seek the lower locations due to gravity. The more active grinding takes place 70 outside the impeller 30 above the position of the lowermost balls. It will be seen that the impeller 30 moves any balls which it contacts at a rate equal to the speed of the impeller. The balls below the impeller 30 can move at a slower speed. 75 Consequently, the higher balls are moved over

and in contact with the lowermost layer of balls. The lowermost layer of balls, however, will have movement and will do considerable grinding. But the movement of the lowermost layer of balls is relatively slow. This is important because it saves wear on the liner members.

The curved fan vanes 37 on the under side of member 35 tend to cause air to pass upwardly through stuffing box 9 thus preventing coal from entering the stuffing box.

10 The air blows in a steady stream through the pulverizer and carries the ground coal away from the grinding zone and upwardly within chamber 13. The mixture of air and pulverized coal passes between the classifying plates 42 and 43 which cause a change in direction of flow of the pulverized material. Any relatively large particles cannot pass through the space between plates 42 and 43 on account of the projections 44 which throw such particles outwardly by centrifugal 20 force, allowing them to fall back into the grinding zone. The mixture of air and powdered coal passes through the tangential outlet 41 to the point of use. The tangential outlet provides further classification to that provided by the classifying plates 42 and 43. It will be seen that there is an expansion above the plates 42 and 43 as a result of which heavier particles will settle out of the air-fuel mixture.

30 My invention has various advantages. Probably the most important are the efficient grinding action and the minimum wear on the liners. It will be obvious that my improved pulverizer has some of the characteristics of a horizontal loose ball mill pulverizer while having the advantage 35 that it requires less floor space and that more efficient grinding can be obtained because of the relative movement of the balls and the rubbing action of the balls against each other. The maintenance cost is low because wear is concentrated 40 in the balls rather than the liners and because new balls may be charged into the pulverizing chamber without dismantling or even stopping the pulverizer. As above pointed out, moreover, a new ball of a diameter slightly less than the clearance space between the bottom of the pulverizing chamber and the impeller 30 may be introduced and may be worn down completely. The efficiency of the herein disclosed ball pulverizer will be high as compared with the ordinary type of ball mill 45 because higher speeds may be used and because of the high grinding pressures and the relative speeds of the balls with respect to each other and with respect to the non-rotating parts.

55 While I have shown but one embodiment of my invention in accordance with the requirements of the patent laws, it will be understood that this is not by way of limitation and that the invention may be embodied in a great variety of structures.

What I claim is:

1. A ball mill pulverizer comprising a stationary, substantially cylindrical, casing having a grinding zone in the lower portion thereof, a plurality of balls in the casing, an impeller mounted in the casing for rotation about a substantially vertical axis, means for rotating said impeller, said impeller having a plurality of blades disposed in said grinding zone, said blades being arranged and disposed in the casing so that the clearance between the lowermost and the outermost portions of the blades and the bottom and side walls respectively of the casing is slightly greater than the diameter of the largest balls 75

in the casing, said impeller blades being hollow and having an outlet opening adjacent the bottom of the casing, a tubular member connected to the impeller blades, means for supplying air and material to be pulverized to said tubular member for introduction into the grinding zone of the casing through the hollow impeller blades, an outlet for the casing and a plurality of spaced plates disposed in the casing between the grinding zone and the outlet for classifying the pulverized material.

2. A ball mill pulverizer comprising a stationary, substantially cylindrical, casing having a grinding zone in the lower portion thereof, a plurality of balls in the casing, an impeller mounted in the casing for rotation about a substantially vertical axis, means for rotating said impeller, said impeller having a plurality of blades disposed in said grinding zone, said blades being arranged and disposed in the casing so that the clearance between the lowermost and outermost portions of the blades and the bottom and side walls respectively of the casing is slightly greater than the diameter of the largest balls in the casing, said impeller blades being hollow and having an outlet opening adjacent the bottom of the casing, a tubular member connected to the impeller blades, and means for supplying air and material to be pulverized to said tubular member for introduction into the grinding zone of the casing through the hollow impeller blades.

3. A ball mill pulverizer comprising a casing, a plurality of balls in the casing, means for introducing material to be pulverized into the casing, an impeller having blades in the casing mounted for rotation about a substantially vertical axis and so as to contact the balls in the casing, the blades of the impeller being hollow, and means for introducing air into the casing through said hollow impeller blades.

4. A ball mill pulverizer comprising a casing, a plurality of balls in the casing, means for introducing material to be pulverized into the casing, an impeller having blades in the casing mounted for rotation about a substantially vertical axis and so as to contact the balls in the casing, the blades of the impeller being hollow, and means for introducing the material to be

pulverized into the casing through said hollow impeller blades.

5. A ball mill pulverizer comprising a stationary casing, a plurality of balls in the casing, means for introducing material to be pulverized into the casing, an impeller having blades in the casing mounted for rotation about a substantially vertical axis and so as to contact the balls in the casing, the blades of the impeller being hollow and having outlet openings in the lower portions of the impeller blades, and means for introducing air into the hollow impeller blades and through said outlet openings into the bottom of the casing.

6. A ball mill pulverizer comprising a stationary casing, a plurality of balls in the casing, means for introducing material to be pulverized into the casing, an impeller having blades in the casing mounted for rotation about a substantially vertical axis and so as to contact the balls in the casing, the blades of the impeller being hollow and having outlet openings in the lower portions of the impeller blades, and means for introducing material to be pulverized into the hollow impeller blades and through said outlet openings into the bottom of the casing.

7. A ball mill pulverizer comprising a casing, a plurality of balls in the casing, means for introducing material to be pulverized into the casing, an impeller having blades in the casing mounted for rotation about a substantially vertical axis and so as to contact the balls in the casing, the blades of the impeller being hollow, a tubular member connected with the impeller blades, and means for supplying air to said tubular member for introduction into the casing through the impeller blades.

8. A ball mill pulverizer comprising a casing, a plurality of balls in the casing, an impeller having blades in the casing mounted for rotation about a substantially vertical axis and so as to contact the balls in the casing, the blades of the impeller being hollow, a tubular member connected with the impeller blades, and means for supplying material to be pulverized to said tubular member for introduction into the casing through the impeller blades.

MARTIN FRISCH.
